CLAIM

The ornamental design for a light emitting diode board, as shown and described.

DESCRIPTION

FIG. 1 is a front side perspective view of a light emitting diode board in accordance with the first embodiment of the our new design;

FIG. 2 is a top plan view of the light emitting diode board in accordance with the first embodiment of our new design;

FIG. 3 is a bottom plan view of the light emitting diode board in accordance with the first embodiment of our new design;

FIG. 4 is a front elevational view of the light emitting diode board in accordance with the first embodiment of our new design;

FIG. 5 is a rear elevational view of the light emitting diode board in accordance with the first embodiment of our new design;

FIG. 6 is a right side elevational view of the light emitting diode board in accordance with the first embodiment of our new design;

FIG. 7 is a left side elevational view of the light emitting diode board in accordance with the first embodiment of our new design;

FIG. 8 is a front side perspective view of a light emitting diode board in accordance with the first embodiment of our new design;

FIG. 9 is a top plan view of the light emitting diode board in accordance with the first embodiment of our new design with a surrounding structure shown in broken lines;

FIG. 10 is a bottom plan view of the light emitting diode board in accordance with the first embodiment of our new design with a surrounding structure shown in broken lines;

FIG. 11 is a front elevational view of the light emitting diode board in accordance with the first embodiment of our new design with a surrounding structure shown in broken lines;

FIG. 12 is a rear elevational view of the light emitting diode board in accordance with the first embodiment of our new design with a surrounding structure shown in broken lines;

FIG. 13 is a right side elevational view of the light emitting diode board in accordance with the first embodiment of our new design with a surrounding structure shown in broken lines;

FIG. 14 is a left side elevational view of the light emitting diode board in accordance with the first embodiment of our new design with a surrounding structure shown in broken lines;

FIG. 15 is a front side perspective view of a light emitting diode board in accordance with the second embodiment of our new design;

FIG. 16 is a top plan view of the light emitting diode board in accordance with the second embodiment of our new design;

FIG. 17 is a bottom plan view of the light emitting diode board in accordance with the second embodiment of our new design;

FIG. 18 is a front elevational view of the light emitting diode board in accordance with the second embodiment of our new design;

FIG. 19 is a rear elevational view of the light emitting diode board in accordance with the second embodiment of our new design;

FIG. 20 is a right side elevational view of the light emitting diode board in accordance with the second embodiment of our new design; and,

FIG. 21 is a left side elevational view of the light emitting diode board in accordance with the second embodiment of our new design.

The broken lines and dotted lines showing the environment (the remaining structure of the light emitting diode board) in the Figures are provided for illustrative purposes only and form no part of the claimed design.
